UNITED STATES PATENT OFFICE.

ORVANDO D. WHITE, OF CHICAGO, ILLINOIS, ASSIGNOR TO ANGELINA SYBILLA WHITE, OF CHICAGO, ILLINOIS.

FRAME FOR TRUNKS, &c.

No. 800,037.

Specification of Letters Patent.

Patented Sept. 19, 1905.

Application filed June 10, 1904. Serial No. 211,907.

To all whom it may concern:

Be it known that I, ORVANDO D. WHITE, a citizen of the United States, residing at Chicago, in the county of Cook and State of Illinois, have invented certain new and useful Improvements in Frames for Trunks, &c., of which the following is a specification.

My invention relates to frames for trunks, boxes, and like articles.

10 The object of the invention is to provide a frame of such novel and peculiar structure that it will be stiffer, more durable, cheaper, lighter, and more easily assembled than under the ordinary methods in present use and which 15 will also save on expensive trunk-hardware now necessary to brace the trunk at all exposed parts.

The invention consists in the matters hereinafter described in connection with the accompanying drawings and then recited in the appended claims.

In the drawings, Figure 1 is a perspective view of a trunk or box made in accordance with my invention, the panels constituting 25 the walls of the device being omitted for convenience in illustrating the frame. Fig. 2 is a partial perspective view of the upper portion of the device of Fig. 1 having the panels in place. Fig. 3 is a vertical section 30 through the front wall of the device of Fig. 1 with the panels in place. Fig. 4 is a vertical sectional view through a corner-post of the frame. Fig. 5 is a detail view showing the various parts of the frame at one corner 35 separated or disassembled along their common line of junction, the posts being broken away for convenience of illustration. Fig. 6 is a detail perspective view showing the arrangement of the side and end pieces of the 40 top frame of the lid. Fig. 7 is a cross-sectional view of the corner-post of Fig. 5. Fig. 8 is a cross-sectional view of a modified form 45 of corner-post. Fig. 9 is a perspective view of a form of brace that may be employed. Fig. 10 is a detail sectional view on the line 10 of Fig. 3. Fig. 11 is a detail perspective view of a form of corner-piece adapted for 50 use in the top frame of the body and the lower frame of the lid. Fig. 12 is a detail perspective view showing an adjustable construction 55 that may be employed. Fig. 13 is a detail perspective view of a form of corner-piece adapted for use in the bottom frame of the body. Fig. 14 is a detail perspective view

of a form of adjustable construction that may 55 be employed for the bottom frame of the body, and Fig. 15 is a sectional view of a modification.

In the accompanying drawings the trunk or box is composed of a body and lid of suitable size and shape and having the side and end boards or panels 1 and 2, respectively, and the bottom and top boards 3. The body of the device is provided with suitable corner-posts 4, which are preferably metallic, such as 60 malleable iron or cast-steel, and each having a pair of wings 5, arranged at right angles at its inner corner and provided at its ends with studs 6, preferably adapted to be headed over in the form of rivets or other suitable fastenings. 65

The bottom frame of the body consists of suitable horizontal side and end rails 7 and 8, respectively, each provided with a central vertical flange 9 on its inner or upper face and 70 somewhat shorter than the body of the rail, the arrangement being such that when the parts are assembled the ends of the flanges 9 abut against the ends of the wing 5, as clearly 75 shown in Fig. 1. The ends of the rails are cut 80 away at 10 in order to make a flush finish at the joints and are provided with holes 11 to receive the lower fastening, such as the stud or rivet 6 of the associated post 4, which being headed secures the rails together and to 85 the post.

The top frame of the body is composed of the horizontal side and end pieces 12 and 13, respectively, having their ends cut away, as at 90 14, in order to provide flush joints and being 15 provided with holes or perforations 15, adapted to receive the top stud 6 of the associated side post, which being headed over secures the side and end rails to each other and to the post. Each of the side and end rails constituting the 95 top frame of the body is provided with a depending vertical flange 16, arranged along its inner edge or margin and somewhat shorter than the rail itself, the arrangement being such that when the parts are assembled the 100 ends of the flanges 16 abut against the wings of the associated posts, as clearly shown in Fig. 3.

It is of course obvious that the frame thus far described when provided with suitable end 105 and side boards or panels constitutes an open-top box or receptacle and that this device may be provided with a cover or lid of any suit-

able construction. When a lid of suitable depth is desired, as is often the case in trunks, I prefer to employ a sectional or knockdown lid of the construction illustrated in Figs. 1 5 and 5. In the construction there shown, 17 and 18 indicate horizontal side and end rails, respectively, having their ends cut away, as at 19, in order to provide flush joints and being perforated, as at 20, to receive the lower 10 stud 6 of a corner-post 4. Each of the side and end rails of the bottom frame of the lid is provided with an upwardly-directed flange 21, arranged along its inner margin, these flanges being somewhat shorter than their associated 15 rails in order to provide space for the wings 5 of the associated corner-post, it being understood that when the parts are assembled the lower stud is headed over to connect the side and end rails to each other and to the 20 post, with the ends of the flanges 21 flush against the wings 5.

The top frame of the lid is composed of the horizontal side and end rails 22 and 23, respectively, each provided with holes or 25 perforations to receive the top stud 6 of the associated corner-post. Each of the side and end rails of the top frame of the lid is provided with a downwardly-extending vertical flange 25, arranged along its inner edge or margin 30 and terminating short of the end of the rails in such manner as to abut against the wings 5 of the associated corner-posts when the parts are assembled. The ends of the side and end rails of the top frame of the lid are cut 35 away, as at 26, to provide flush joints, and each of these rails is further provided with an upwardly-extending flange 27 along its outer edge or margin and coming together flush at the corners, where they are rounded off to provide 40 a suitable finish.

It is obvious that when the boards or panels constituting the body of the box or trunk are assembled upon the frame the bottom board or panel 3 will rest upon the side and end 45 rails, with its edges snug against the flanges 9 and the lower ends of the wings 5 of the corner-posts, and that the board or panel may be suitably secured in place by means of rivets or other suitable fastening devices passing 50 through the rails. The side panels will fill the spaces between the rails 7 and 12 and the corner-posts 4 and may be suitably secured to the flanges 5, 9, and 16. The end panels will fill the spaces between the end 55 rails 8 and 13 and the corner-posts and may be suitably secured to the associated flanges 5, 9, and 16. The top panel of the lid will rest upon the side and end rails 22 and 23 within the space bounded by the outer flange 60 27 and may be suitably secured in place by fastenings passing through the rails. The side panels of the lid will fill the spaces bounded by the rails 17 and 22 and the posts 4 and may be suitably secured in position by fastening devices passing through the flanges 5, 65

21, and 25. The panels for the ends of the lid will occupy the spaces between the rails 18 and 23 and the post 4 and may be suitably secured by fastening means passing through the flanges 5, 21, and 25.

It is of course understood that the top or lid of the device may be hinged to the body by any suitable means.

In Fig. 8 I have shown a modified form of 75 a corner-post, in which the body of the post is provided with outer wings 28, it being obvious that these wings serve to confine and brace the side and end panels.

Suitable braces may be employed wherever 80 desired, and in Fig. 9 I have shown a form of brace which may be conveniently used. This brace is substantially T-shaped in cross-section and may be secured at its ends to the flanges of the side or end rails. In Fig. 3 I have illustrated an application of the use of 85 this brace where it is shown attached to the flanges 9 and 16, it being understood that the material of the panel is suitably routed out or kerfed in order to receive the rib 30 of the brace.

In order to provide for trunks of different 90 sizes or dimensions, I may make the side or end rails, or both, adjustable. For this purpose I provide a sectional rail with a suitable 95 filler-piece 31, which preferably is adapted to make a smooth joint or connection with the ends of the associated rails, as by cutting away the meeting ends, as shown in Figs. 12 and 14. It is obvious that as these filler-pieces may be of various lengths the size or dimension 100 of the frame may be correspondingly varied. This is a matter of advantage inasmuch as the parts may all be made of standard or uniform size adapted to coöperate and be assembled with different sizes of 105 filler-pieces, so that the manufacturer, being provided with different lengths of filler-pieces, may construct a trunk of any size or dimension desired. In Fig. 12 I have shown a suitable 110 filler-piece adapted to the top rail of the body or to the lower rail of the lid and in Fig. 14 a similar filler-piece adapted to the lower rail of the body. It is obvious that in a similar manner the top rail of the lid may be made adjustable. The filler-pieces may be 115 made in different lengths or they may be made in long strips adapted to be cut into different lengths by the manufacturer to fit any-size trunk, thus making it easy to construct a receptacle of any desired dimensions. 120

It is obvious that the side and end rails of the various frames may be made integral. For example, in Figs. 11 and 13, respectively, I have shown such integral constructions. In Fig. 11 two of the rails of either the top 125 frame of the body or the bottom frame of the lid are integral to form a corner-plate 32, which is provided at its angle with a suitable perforation to receive one of the studs of the corner-post, and in Fig. 13 I have shown two 130

of the rails of the bottom frame of the body integral to form a corner-plate 33, similarly perforated for its associated stud. It is also obvious that the corner-plates of the frames 5 may be made integral in the manner shown in Figs. 11 and 13 and assembled in conjunction with filler-pieces 31, as shown in Figs. 12 and 14, respectively.

All of the parts are preferably metallic, and 10 it is obvious that the various portions of the frame may be made and shipped in knock-down form to be readily assembled by the manufacturer or the entire frame for the body may be cast integral and the entire frame of 15 the lid may also be cast integral; also, the parts may be made in various standard sizes for trunks of different dimensions and by the sectional arrangement or construction of various portions of the frame the manufacturer 20 may carry in stock all the parts necessary to make up a trunk of any desired size at a moment's notice.

The form of corner-post protects the ends 25 of the panels or boards at all points where they would otherwise be exposed and liable to split in handling and the posts save the expense of corner-irons and other parts of trunk-hardware now generally used.

The solid corner plates or pieces add to the 30 rigidity of the structure and in connection with the sectional rails provide a simple form of frame for ready use in making up receptacles of various sizes.

The nails, rivets, or screws employed pass 35 through the panels and wings of the posts or flanges of the rails, thus holding the panels securely in place.

It is obvious that the frames may be solid 40 or in sections united at their corners or with solid corner-plates and associated filler-pieces, all of which forms are described and shown.

In Fig. 15 I have shown an outer supplemental flange 34 to protect the edge of the panel, and it is obvious that such flanges may 45 be employed on the other horizontal parts of the frame. These supplemental flanges will align with the wings 28 of the corner-posts when both are employed.

Having described my invention, I claim— 50 1. In a device of the class described, a corner-post having angular wings, and a frame composed of strips having flanges in extension of said wings.

2. In a device of the class described, a corner-post having inner wings at a right an-

gle to each other, and a frame composed of strips having inner flanges abutting the wings.

3. In a device of the class described, a corner-post having angular wings, and a top and bottom frame each having flanges in extension of said wings. 60

4. In a device of the class described, a corner-post having angular wings and an end stud, and a perforated frame having flanges adapted to align with the wings when the stud 65 enters its associated perforation.

5. In a device of the class described, a corner-post having angular inner wings and end studs, and top and bottom frames each having inner vertical flanges and corner-perforations, 70 the studs securing the frames to the posts with the adjacent wings and flanges in alignment.

6. A post having a body provided with wings extending in angular relation to each 75 other and having permanent studs at its ends adapted to be headed over.

7. In a device of the class described, a corner-post having wings, and a top and bottom frame each provided with flanges in alignment 80 with the wings, the top frame also having flanges for the top panel.

8. In a device of the class described, a corner-post having inner wings, and a top and bottom frame each having inner flanges in 85 alignment with the wings, the top frame also having outer flanges for the top panel.

9. In a device of the class described, a corner-post having inner wings, and a top and bottom frame, the latter having flanges in 90 alignment with the wings and the former composed of a strip having inner and outer marginal flanges.

10. In a device of the class described, corner-posts, sectional rails connected at their 95 ends to the corner-posts and adapted to provide constructions of varying sizes, and panels secured to the rails.

11. In a device of the class described, a frame having inner vertical flanges, and a brace secured to the flanges within the front plane of the frame and having a rib adapted to a groove in the associated panel. 100

In testimony whereof I affix my signature in presence of two witnesses.

ORVANDO D. WHITE.
